TABLE MOUNTING DEVICE FOR
CHILDREN'S HIGH CHAIRS

Gedor W. Aldeen, Rockford, Ill., assignor to
American Cabinet Hardware Corporation,
Rockford, Illinois, Rockford, Ill., a corporation
of Illinois

Application November 21, 1945, Serial No. 630,015

3 Claims. (Cl. 155—127)

1

The invention pertains to children's high-chairs, and has more especial reference to devices for mounting the tables of such chairs upon the side arms.

One object of the invention is to provide a table mounting device permitting adjustment of the table in a front-to-rear direction along the arms and swinging movement of the table into a depending position forwardly of the arms with the table pivotally suspended so as to facilitate placement of the child in the chair.

A further object is to provide for easy and convenient adjustment of the table along the arms and to permit of removal of the table entirely when desired.

A general object is to provide a table mounting device of a practical character, simple in construction and susceptible of manufacture at low cost.

The objects of the invention thus generally set forth, together with other and ancillary advantages, are attained by the construction and arrangement shown by way of illustration in the accompanying drawings, in which:

Figure 1 is a plan view of a highchair equipped with mounting devices for the table, constructed in accordance with my invention.

Fig. 2 is a side view of the same and illustrating in broken lines the position of the table in its suspended relation to the side arms.

Fig. 3 is an enlarged fragmentary sectional view of the mounting device with the table in its upright or suspended position at the forward end of one of the side arms.

Fig. 4 is a fragmentary plan view of the mounting device with the table shown in broken lines.

Fig. 5 is a fragmentary side view of the mounting device attached to one of the side arms.

Fig. 6 is a fragmentary sectional view taken in the plane of line 6—6 of Fig. 5.

In the illustrative embodiment of my invention selected for purposes of illustration I have shown the upper portion of a child's highchair comprising a seat 7, a back 8 and side arms 9. A table 10 is mounted on the arms 9 through the medium of mounting devices generally designated 11, one for each arm.

Each mounting device comprises in general a bar 12 having an elongated slot 13 and adapted for attachment to the side arm 9; a bracket 14 to be fastened to the underside of the table near one end thereof and having a bearing element in the form of a lug 15 projecting laterally in spaced relation to the underside of the table for reception by the slot 13; and a locking detent in the

2

form of a lever 16 pivoted upon the bracket 14 and having a locking finger 17 for engagement with spaced notches 18 in one edge of the slot 13. The arrangement is such that when the locking lever 17 is held upwardly to disengage its finger from a notch 18 the table may be slid lengthwise of the slot 13, and in the extreme forward position of the table, it is adapted to swing downwardly into the suspended position shown in Figs. 2 and 3.

The bar 12 is preferably of channel shape as shown in Fig. 6 and is secured to the side arm 9 in such a way that the channel is closed laterally except for the slot 13. As shown, the channel bar 15 has an outer wall portion 19 disposed in a vertical plane in outwardly spaced relation to the inner wall of a recess 9a cut in the side arm and substantially flush with the portion of the arm rearwardly of the recess. The bar also has a lower flange 20 and a top flange 21, the latter being extended for attachment to the upper side of the arm 9 which may be formed with a shallow recess to receive the flange flush with the upper surface of the arm. The slot 13 of the wall portion 19 of the channel bar extends substantially throughout the length of the bar terminating just short of the rear end which is attached to the side arm as by means of a screw 22. At its forward end the bar has a short front flange 23 closing the forward end of the recess 9a.

The bracket 14 is in the form of an angle plate secured by screws 25 to the underside of the table and having a depending portion 26 extending along the outer face of the bar and carrying the lug 15 in vertically spaced relation to the table. The lug is thereby supported for movement along the slot adjacent the upper edge of the latter.

The locking lever 16 extends generally horizontally along the bracket 14. Its rear end is mounted on a pivot pin 27 carried by the depending portion 26 of the bracket, and it is urged downwardly by means of a torsion spring 28 coiled on the pivot stud 27 and having one arm bearing against the underside of the bracket and another arm engaging with a lug 29 struck out from the lever 16. Downward movement of the lever from the spring is limited by a stop lug 30 formed on the bracket and underlying the lower edge of the lever. The locking finger 17 is disposed near the forward end of the lever in opposed relation to the bracket lug 15, the ends of the lug and finger being preferably turned in opposite directions as shown in Fig. 6.

The forward end of the locking lever is guided for vertical movement between the depending

portion 26 of the bracket and a guide lug 31 struck out from the bracket; and the extreme forward end of the lever is provided with a finger-piece 32 for convenience in swinging the locking lever upwardly against the action of its spring.

It will be seen that by lifting the free ends of the levers at opposite ends of the table the fingers 17 will be disengaged with respect to the notches 18 so that the table may be slid in a front-to-rear direction with respect to the arms. Upon release of the levers after disengagement from one set of notches the levers will be urged downwardly by their respective springs so as to carry the locking fingers into engagement with the next succeeding pair of notches 18.

When the table is adjusted into its extreme forward position it will swing downwardly by the force of gravity upon the lugs 15 and locking fingers 17 disposed in opposed relation (Figs. 3, 5 and 6) and acting as pivots, it being observed in this connection that the brackets 14 are attached somewhat rearwardly of the center of the table. With the table thus suspended as shown in broken lines in Fig. 2, it is capable of being swung easily so that it will yield under the pressure of the child's feet, thereby greatly facilitating the placement of the child in the chair.

When the table is in its foremost suspended position it may be easily removed entirely from the chair. For this purpose, the extreme forward ends of the slots 13 in the bars 12 open upwardly for communication with upwardly opening notches 33, the latter in turn communicating with horizontally disposed slots 34 in the top flange 21 (Figs. 3 and 4), the slots being enlarged at their inner ends so as to permit free passage of the bracket lugs 15 and locking fingers 17.

I claim as my invention:

1. A table mounting device for highchairs having side arms comprising, in combination, an elongated supporting bar adapted for attachment to a side arm of the chair and provided with an elongated horizontally disposed slot, a bracket having a flange for attachment to the underside of the table and having a bearing element engaging in said slot and movable longitudinally thereof, and means for locking the bracket in selected positions along the slot, said bearing element pivotally supporting the bracket at the forward end of the slot so as to permit the table attached to the bracket to swing downwardly into suspended relation to the supporting bar, said bearing element being offset downwardly from the flange of the bracket so as to provide clearance between the table and the forward end of the slotted bar in the swinging movement of the table relative to the bar.

2. A table mounting device for highchairs having side arms comprising, in combination, an elongated supporting bar adapted for attachment to a side arm of the chair and provided with an elongated horizontally disposed slot, a bracket for attachment to the table and having a bearing element engaging in said slot and movable longitudinally thereof, means for locking the bracket in selected positions along the slot comprising a locking member carried by the bracket in opposed relation to said bearing element, said slot having notches along one edge for engagement by said locking member, and said bearing element pivotally supporting the bracket at the forward end of the slot so as to permit the table attached to the bracket to swing downwardly into suspended relation to the supporting bar.

3. A table mounting device for highchairs having side arms comprising, in combination, an elongated bar adapted for attachment to a side arm of the chair and provided with an elongated horizontally disposed slot with a notch along one edge, a bracket for attachment to the table and having a bearing element slidable in said slot, and a locking member carried by said bracket in opposed relation to said bearing element and spring pressed into holding engagement with said notch.

4. A table mounting device for highchairs having side arms comprising, in combination, an elongated bar adapted for attachment to a side arm of the chair and provided with an elongated horizontally disposed slot with a plurality of notches along its lower edge, a bracket for attachment to the table and having a bearing element slidable in said slot and constituting a pivot for suspending the bracket at the forward end of the slot, a locking member pivoted on said bracket and having a locking finger disposed in opposed relation to said bearing element on the bracket, and a spring urging said member in a direction to carry said locking finger into a selected one of the notches, said member having a laterally projecting finger-piece at its forward end for operating the member against the action of said spring.

5. A table mounting device for highchairs having side arms comprising, in combination, a channel shaped supporting bar adapted for attachment to the chair side arm so as to coat therewith in forming a closed channel, said channel bar having an elongated wall portion disposed in a vertical plane at the outer side of the arm and formed with an elongated slot, a bracket for attachment to the underside of the table and having a depending portion with a laterally projecting lug thereon engaging one edge of said slot, a locking lever pivoted on said depending portion of the bracket and having a laterally projecting locking finger in opposed relation to said lug, said slot in the channel member having a notch therein, and a spring acting upon said lever to hold said finger in engagement with said notch.

6. A table mounting device for highchairs having side arms comprising, in combination, a channel shaped supporting bar adapted for attachment to the chair side arm so as to coat therewith in forming a closed channel, said channel bar having an elongated wall portion disposed in a vertical plane at the outer side of the arm and formed with an elongated slot, a bracket for attachment to the underside of the table and having a depending portion with a laterally projecting lug thereon engaging one edge of said slot, a locking lever pivoted on said depending portion of the bracket and having a laterally projecting locking finger in opposed relation to said lug, said slot in the channel member having a notch therein, and a spring acting upon said lever to hold said finger in engagement with said notch, said channel member having a notch in its top wall communicating with said slot at the forward end of the latter and adapted to permit passage of said lug and said locking finger in disengaging the bracket from the supporting bar.

7. A table mounting device for highchairs and the like having side arms comprising, in combination, two members respectively adapted for attachment to a side arm of the chair and said table, one of said members having an elongated slot and the other a bearing member engageable

with said slot to permit of a front-to-rear movement of the table and operative in a forward position of the table to permit a downward swinging movement thereof, said one member having a positioning notch at one edge of said slot and the other having a detent slidably in said slot and manually movable transversely of said slot into and out of engagement with said positioning notch.

8. For a child's highchair having side arms and a table to be supported thereby, a bar having an elongated slot therein and adapted to be secured to one side of a chair arm with the slot extending to the forward end of the arm, and a bracket having a flange adopted to be secured to the underside of the table and a bearing element depending from said flange and slidably in said slot, said bar having at its forward end an upwardly opening notch to permit passage of

said bearing element in disengaging the bracket from the bar.
